UNITED STATES PATENT OFFICE

CORNELIUS BROWN, OF BEIRUT, OKLAHOMA

DEVICE FOR REMOVING PARTS FROM WELLS

Application filed July 23, 1930. Serial No. 470,182.

This invention relates to a novel device for removing drilling tools and other parts from a well and the invention has as one of its objects to provide a device for this purpose which may be very conveniently employed and which will prove readily efficient in automatically gripping and holding the drill bit, well tubing, or other parts, which may have become lodged in a well frame.

10 This invention also consists in certain other features of construction and in the combination and arrangement of the several parts to be hereinafter fully described, illustrated in the accompanying drawings, and specifically pointed out in the appended claims, it being understood of course that minor changes may be made so long as they fall within the scope of the claims.

In describing my invention in detail, reference will be had to the accompanying drawings, wherein like characters denote like or corresponding parts throughout the several views, and in which:

Figure 1 is a vertical sectional view illustrating one embodiment of the invention, the parts being shown in the positions which they will assume at the time the device is inserted into a well tube.

Figure 2 is a similar view illustrating the positions assumed by the parts when the device is being drawn upwardly out of the well tube and has gripped the part to be removed from the well.

Figure 3 is a horizontal sectional view taken on the line 3—3 of Figure 2, looking in the direction indicated by the arrows.

Figure 4 is a similar view on the line 4—4 of Figure 2.

Figure 5 is a view similar to Figure 1, illustrating a modification of the invention.

Figure 6 is a horizontal sectional view taken substantially on the line 6—6 of Figure 3, looking in the direction indicated by the arrows.

In the drawings the numeral 1 indicates in general a well tube and in Figure 1 of the drawings two sections of the tube are illustrated and are shown connected by a coupling collar 2. The device embodying the invention comprises a hollow tubular barrel 3

which is provided in its upper end with an opening 4 and this barrel is exteriorly of a diameter to fit freely, slidably, within the well tube 1, or the sections of which said tube is made up.

A stem 5 is slidably fitted through the opening 4 and is exteriorly threaded at its lower end, as at 6 and this stem is provided at its upper end with an integral circumscribing collar and a compression spring 8 is arranged upon the stem and bears at its lower end against the upper end of the barrel 3 and at its upper end against the under side of the collar 7. Above the collar 7, the stem is formed with a threaded conical end 9 by means of which it may be connected with any part of a well drilling apparatus or well pumping apparatus, whereby the device of the invention may be lowered into the well tube 1 to engage and grip the part to be removed and then pulled upwardly through the said tube.

A sleeve 10 is interiorly threaded at its upper end as at 11 and this sleeve is fitted onto the lower threaded end 6 of the stem 5. The sleeve is exteriorly of a diameter to fit freely, slidably in the barrel 3 and this sleeve is formed at its lower portion with diametrically, oppositely located, vertically extending recesses 12 which provide diametrically, oppositely located clamping members 13 which of course extend downwardly from the undivided portion of the sleeve, and each of these clamping portions is provided upon its inner side, and at its lower end, with an inwardly projecting portion 14 which is adapted to engage beneath a head or collar 15 at the upper end of a pipe section or the like indicated by the numeral 16, this collar or head and pipe section being shown in dotted lines in Figure 2. It will be observed that the inner sides of the portions 14 are downwardly and outwardly inclined, and at their upper sides are flat so that when the sleeve 10 is lowered and brought into engagement with the upper end of the part to be removed, the portions 14 will readily ride over said end of the part until their upper sides engage beneath the upper side of the head or flange upon said part.

Mounted within the sleeve 10 is a stem 17 which is provided at its upper end with a flat circular head 18 of a diameter to fit slidably within the sleeve 10 and, intermediate 5 its ends with a similar head 19. A compression spring 20 is arranged within the sleeve 10 and bears at its upper end against the lower end of the stem 5 and at its lower end against the upper side of the head 18 upon 10 the stem 17.

Below the head 19, the stem is formed with a diametric slot 21 in which are pivotally mounted the inner ends of fingers 22, the outer ends of the fingers being beveled as indicated by the numeral 23. Each of the clamping members 13 is formed with a vertical series of openings 24, and similar openings are likewise formed in the lower portion of the sleeve above the recesses 12, and these 15 openings are of a size to permit of the extension of the fingers 22 therethrough. Each opening 24 has a horizontal top wall, as will be observed by reference to Figures 1 and 2, and a downwardly and outwardly inclined 20 bottom wall 25, and it will be evident by a comparison of Figures 1 and 2, that the fingers 22 may assume a horizontal position engaging at their upper sides against the under side of the head 19 and projecting through 25 any pair of the openings 24 so as to engage beneath the lower end of the barrel 3 and, where the device is lowered into a well tube comprising sections, the outer ends of the fingers may engage also in the space between 30 the lower end of the upper section and upper end of the lower section of the well tube. The lower end of the stem 17 is preferably located somewhat below the lower head 19 and therefore below the pivoted ends of the 35 fingers 22, and therefore is adapted to come into engagement with the upper end of the drill bit, pipe section, or other part, which is to be removed by the use of the device, when the device has been lowered into the well tube 40 a sufficient distance.

As stated above, the portions 14 of the clamping members 13 are adapted to ride over a collar or shoulder or head upon a bit or pipe section, and therefore the sleeve 10 45 will preferably be made of steel so as to possess the required degree of resiliency to permit of a slight stretching of the members 13, for this purpose. By reference to Figures 1 and 2 it will be observed that when the device is lowered into the well tube the upper 50 spring 8 will be permitted to expand due to the upward shifting of the stem 17 through the engagement of this stem against the upper end of the part to be removed and, at such 55 time, the sleeve 10 will be moved upwardly into the barrel 3 and the stem 5 will likewise be moved upwardly through the opening 4 in the barrel and, in this upward movement 60 of the stem 17, the spring 20 will be compressed due to the engagement of the upper 65

end of the sleeve 10 against the upper end of the barrel 3, and likewise due to the binding of the outer ends of the fingers 22 in the openings 24 in which they are engaged, and therefore a direct upward pulling force will be 70 imposed, by the device, upon the part to be lifted or removed from the well tube.

In the preceding embodiment of the invention, the device is designed primarily for use 75 in removing drills or other parts having heads or collars beneath which the parts 14 of the clamping members 13 might engage, but inasmuch as it is at times necessary to remove a threaded pipe section, the embodiment illustrated in Figures 5 and 6 is designed for this particular use, and inasmuch as, except for the difference in the formation 80 of the clamping members 13, this embodiment does not in any way differ from the one shown in Figures 1 to 4 inclusive, the same reference 85 numerals, primed, are employed to indicate like parts.

In this embodiment, each clamping member 13' instead of being formed with a head such as the head 14 is formed upon its inner 90 side with threads 26 so that these threads may be brought into engagement with the threads 27 at the upper end of a pipe 28 which is to be removed.

What I claim is:

1. In a device for removing drilling tools and other parts from a well, a hollow tubular barrel, a stem having a threaded upper end to adapt it to be connected to a part working in the well for up and down movement, the said stem fitting slidably through the upper end of the barrel, and having an abutment near its upper end, a compression spring fitting the said stem and bearing between the abutment and the said end of the barrel, a sleeve fitted, at its upper end, to the lower end of the stem, clamping members extending downwardly from the lower end of the sleeve and having inwardly directed portions to engage beneath a head, or the like, upon the part to be removed, a stem having spaced heads slidably fitting in the sleeve, the sleeve being formed, in each of its clamping members with a series of openings, and fingers pivotally mounted, at their inner ends in the lower portion of the stem and engageable, at their outer ends in the said openings in the respective clamping members.

2. In a device for removing drilling tools and other parts from a well, a hollow tubular barrel, a stem having a threaded upper end to adapt it to be connected to a part working in the well for up and down movement, the said stem fitting slidably through the upper end of the barrel, and having an abutment near its upper end, a compression spring fitting the said stem and bearing between the abutment and the said end of the barrel, a sleeve fitted, at its upper end, to the lower end of the stem, clamping members extending downwardly 125

from the lower end of the sleeve and having inwardly directed portions to engage beneath a head, or the like, upon the part to be removed a stem having spaced heads slidably fitting in the sleeve, a compression spring within the sleeve engaging between the upper one of the heads, upon the stem, and the lower end of the first mentioned stem, the sleeve being formed, in each of its clamping members with a series of openings, and fingers pivotally mounted, at their inner ends in the lower portion of the stem and engageable, at their outer ends, in the said openings in the respective clamping members.

5 3. In a device for removing drilling tools and other parts from a well, a hollow tubular barrel, a stem having a threaded upper end to adapt it to be connected to a part working in the well for up and down movement, the 10 said stem fitting slidably through the upper end of the barrel, and having an abutment near its upper end, a compression spring fitting the said stem and bearing between the abutment and the said end of the barrel, a 15 sleeve fitted, at its upper end, to the lower end of the stem, clamping members extending downwardly from the lower end of the sleeve and having inwardly directed portions to engage beneath a head, or the like, upon the 20 part to be removed, a stem having spaced heads slidably fitting in the sleeve, the sleeve being formed, in each of its clamping members with a series of openings, and fingers pivotally mounted, at their inner ends in the 25 lower portion of the stem and engageable, at their outer ends in the said openings in the respective clamping members, the upward swinging movement of the fingers being limited by their engagement against the 30 under side of the lower head upon the stem.

35 4. In a device for removing drilling tools and other parts from a well, a hollow tubular barrel, a stem having a threaded upper end to adapt it to be connected to a part working 40 in the well for up and down movement, the said stem fitting slidably through the upper end of the barrel, and having an abutment near its upper end, a compression spring fitting the said stem and bearing between the 45 abutment and the said end of the barrel, a sleeve fitted, at its upper end, to the lower end of the stem, clamping members extending downwardly from the lower end of the sleeve and having threads upon their inner 50 sides to engage with a threaded part to be removed, a stem having spaced heads slidably fitting in the sleeve, the sleeve being formed, in each of its clamping members with a series of openings, and fingers pivotally mounted, at their inner ends, in the 55 lower portion of the stem and engageable, at their outer ends in the said openings in the respective clamping members.

60

In testimony whereof I affix my signature.
CORNELIUS BROWN.
